UNITED STATES PATENT OFFICE

96,186

DESIGN FOR A PLATE OR SIMILAR ARTICLE

Frank P. Judge, Coshocton, and Eber Merrill
Owens, East Liverpool, Ohio

Application January 26, 1935, Serial No. 55,078

Term of patent 3½ years

To all whom it may concern:

Be it known that we, Frank P. Judge and Eber Merrill Owens, citizens of the United States, residing at Coshocton, in the county of Coshocton and State of Ohio, and East Liverpool, in the county of Columbiana and State of Ohio, respectively, have invented a new, original, and ornamental Design for a Plate or Similar Article, of which the following is a specification, reference being had to the accompanying drawing, forming part thereof.

The figure is a plan view of a plate, showing our new design, the ornamentation being continued around the entire border of the plate.

We claim:

The ornamental design for a plate or similar article, as shown and described.

FRANK P. JUDGE.
E. MERRILL OWENS
